(57) **CLAIM**

The ornamental design for a cap for pharmaceutical containers, as shown and described.

DESCRIPTION

FIG. 1 is a perspective view of a cap for pharmaceutical containers;

FIG. 2 is a top plan view thereof;

FIG. 3 is a bottom plan view thereof;

FIG. 4 is a front elevation view thereof;

FIG. 5 is a rear elevation view thereof;

FIG. 6 is an elevation view thereof from the right side; and,

FIG. 7 is an elevation view thereof from the left side.

The broken line showing of the cap for pharmaceutical containers is for the purpose of illustrating portions of the cap for pharmaceutical containers and forms no part of the claimed design.

1 Claim, 7 Drawing Sheets(56)
